(57) **CLAIM**

The ornamental design for a bracket for a handheld cleansing device, as shown and described.

DESCRIPTION

FIG. 1 is an isometric view of an embodiment of a bracket for a handheld cleansing device with certain components shown in dashed lines for environment.

FIG. 2 is a top, front isometric view of the bracket for a handheld cleansing device of FIG. 1.

FIG. 3 is a front elevation view of the bracket for a handheld cleansing device of FIG. 1.

FIG. 4 is a rear elevation view of the bracket for a handheld cleansing device of FIG. 1.

FIG. 5 is a right side elevation view of the bracket for a handheld cleansing device of FIG. 1.

FIG. 6 is a left side elevation view of the bracket for a handheld cleansing device of FIG. 1.

FIG. 7 is a top plan view of the bracket for a handheld cleansing device of FIG. 1; and,

FIG. 8 is a bottom plan view of the bracket for a handheld cleansing device FIG. 1.

The broken lines, which define the bounds of the claimed design, form no part of the claimed design.

1 Claim, 5 Drawing Sheets
